UNITED STATES PATENT OFFICE

VANCE C. GARRISON, OF NEBISH, MINNESOTA

WRENCH

Application filed November 11, 1930. Serial No. 494,962.

This invention relates to wrenches, the jaws of which are adapted to be quickly and conveniently adjusted to engage various sizes of nuts, bolts, and the like and which are operable to engage the nuts, bolts and the like through the medium of the usual screw means.

The primary object of this invention is to provide a wrench with a stationary jaw and a cooperating movable jaw, the movable jaw of which is adapted to be freely, rapidly, and solidly adjusted to engage different sizes of nuts, bolts and the like by instantly disengaging the actuating means from the movable jaw at the will of the operator, or if desired the actuating means can be operated to feed the movable jaw to engage various sizes of nuts, bolts and the like in the conventional manner.

These and other objects, the nature of the invention, its composition and arrangement and combination of parts will be readily understood by any one acquainted with the art to which this invention relates upon consulting the following descriptions of the drawings, in which:

Figure 1 is a side elevational view of my improved wrench.

Figure 2 is a transverse vertical section 30 through Figure 1 showing the details of construction and arrangement of parts.

Figure 3 is a transverse vertical cross-sectional view through the operating worm and its shaft.

Figure 4 is a detailed similar cross sectional view of the ramp structure.

Figure 5 is an edge elevational view of the element disclosed in Figure 3.

Referring in detail to the drawings the numeral 5 designates generally a wrench of the type described having the stationary jaw 6 and the movable jaw 7. The stationary jaw has a transverse passage therethrough designated 8, and an angular socket 9 leading into the opening 8. In the socket 9 is a helical spring 10 pressing against the bottom of the socket and outwardly and upwardly forcing the end of a pin 11 on which is rotatably mounted a worm screw 12 having laterally beveled threads 13, oppositely

beveled to the teeth 14 on a longitudinal rack bar on the lower edge of the movable jaw 7. The pin 11 is adapted to be mounted across the opening 8 and to project a downwardly turned finger portion 15 into the upper convolution of the spring 10, and the other end of the pin 11 is provided with an annular shoulder 16 for limiting the movement in a longitudinal direction of the worm 12. Outside of the shoulder 16 the normal contour of the pin 11 continues for a short distance where it is formed with a reduced portion 17 the outer end of which is downwardly and inwardly beveled as shown at 18 for engaging a ramp 19 formed in a screw plug 20 which is screw threadedly projected through one side of the stationary jaw 6. A longitudinally projecting stop member 21 is mounted just above the ramp 19 to limit the upward projection of the end portion 17 of the pin 11.

Apart from the fact that the teeth 14 of the rack on the movable jaw 7 are laterally beveled so as to have a longitudinally deflected angular face it is of conventional type with the exception of a downwardly projected foot portion 22 which is adapted to act as a stop member for limiting the outward movement of the movable jaw 7, since it is disposed to strike the adjacent or contiguous end of the worm screw 12. An examination of Figure 2 and Figures 3 and 4 of the drawings discloses the fact that the pin 11 is normally so disposed that the worm screw 12 is normally projected into engagement with the teeth of the rack 14, the finger 15 being disposed in the upper convolution of the spring 10 and the opposite end of the pin 11 rested on the ramp 19 slightly spaced from the stop member 21.

Thus the worm screw 12 is normally projected into mesh with the rack teeth 14, and in this position the usual manner of operation of a wrench of this type is obtainable by rotating the screw 12 on the pin 11. Should a quick adjustment of the jaw be required to a smaller size, it is obvious that a quick direct pressure on the movable jaw 7 inwardly will result in the yielding of the spring 10 to permit said sliding motion by freeing the

screw 12 out of the teeth 14 due to the climbing of the beveled teeth over each other. It is believed obvious that when the sliding movement has ceased, the spring 10 will urge 5 the screw 12 into mesh with the teeth 14 to resist opening of the jaw under the pressure of the work. Of course, it is obvious that when the wrench is desired to be quickly and rapidly opened, the screw may be depressed 10 against the action of the spring 10 to free the teeth and the screw threads of the screw out of engagement to permit the free sliding of the movable jaw 7. The wrench is so constructed that at no time is the screw 12 so 15 much depressed that it will not any longer act as a stop to meet the stop member 22 on the movable jaw of the wrench, thus providing that at all times the said movable jaw be positively and effectively prevented from being displaced from assembly with the rest of the wrench or too far opened.

It is thought also to be obvious that when the movable jaw 7 has been roughly adjusted by the said quick sliding motion, the screw 25 12 may be brought into action to make a finer adjustment of the said position of the movable jaw 7.

One of the main advantages of my wrench 30 is that the greater the pressure which tends to open the movable jaw 7, the greater the engagement of the screw with the teeth of the rack 14 will be, since longitudinal pressure will cause the pin 11 to have a thrust toward the ramp 19, which will cause an upward motion of the pin 11 and a consequent more powerful engagement of the threads of the screw 12 with the teeth 14 of the movable jaw 7. It has already been pointed out that the spring 10 has an upward, and, with respect to the pin 11, a longitudinal pressure 35 which maintains the pin and its worm screw 12 properly positioned for all of the said actions of the wrench. Thus the greater the pressure which is brought to bear on the wrench while it is being used, the greater the security of the engagement of the parts so 40 that the rigidity of adjustment which is obtained thereby is such as has not been heretofore achieved in a wrench of this type.

It will now be evident that I have provided 45 a wrench of the type described which embodies features of extraordinary efficiency and handiness as well as qualities of power, fine and rapid adjustment, and other features of 50 novelty and advantage which will be evident as growing out of the above description of the parts and their cooperation which make up my improved wrench.

It is to be definitely understood that I do 55 not desire to limit the application of this invention to the particular modification set out herein to illustrate the principles thereof, and any change or changes may be made 60 in structure and material and arrangement

of parts consistent with the spirit and scope of the invention.

What is claimed is:—

1. A quick adjustable wrench of the type described comprising a handle portion carrying a stationary jaw and a jaw guide, a jaw movable on said guide for cooperation with said stationary jaw, a transverse opening in said handle portion below said guide, an angularly disposed socket communicating through one vertical wall of said opening, a freely mounted pin, a spring in said socket for carrying one end of said pin, a worm screw rotatable on said pin, a ramp engaging face on the other end of the pin, and a ramp mounted in the wall of said opening opposite said socket, said movable jaw provided with a bevel toothed rack on its under edge for cooperation with said worm screw, said spring adapted to normally urge said pin for projecting the worm screw into cooperation with the toothed rack of the movable jaw, and causing the said ramp engaging face to climb the said ramp for increasing the locking effect of said worm screw with the rack substantially proportionally to the pressure brought to bear upon the work. 70 75 80 85

2. A quick adjustable wrench of the type described comprising a handle portion carrying a stationary jaw and a jaw guide, a jaw movable on said guide for cooperation with said stationary jaw, a transverse opening in said handle portion below said guide, an angularly disposed socket communicating through one vertical wall of said opening, a freely mounted pin, a spring in said socket for carrying one end of said pin, a worm screw rotatable on said pin, a ramp engaging face on the other end of the pin, and a ramp mounted in the wall of said opening opposite said socket, said movable jaw provided with a bevel toothed rack on its under edge for cooperation with said worm screw, said spring adapted to normally urge said pin for projecting the worm screw into cooperation with the toothed rack of the movable jaw, and causing the said ramp engaging face to climb the said ramp for increasing the locking effect of said worm screw with the rack substantially proportionally to the pressure brought to bear upon the work, said ramp 90 95 100 105 110 115 120 125

In testimony whereof I affix my signature.

VANCE C. GARRISON.
